TEMPERATURE SENSING PROBE

Martin J. Oudewaal, Del Mar, Calif., assignor to
Diatek, Inc.

Filed Jan. 19, 1972, Ser. No. 219,204

Term of patent 14 years

Int. Cl. D10—04

U.S. Cl. D52—7 R

FIG. 1 is a perspective view of a temperature sensing probe showing my new design;

FIG. 2 is a side elevational view thereof, the wire lead shown broken away for ease of illustration;

FIG. 3 is a left end elevational view of FIG. 2; and
FIG. 4 is a right end elevational view of FIG. 2, the wire lead shown broken away for ease of illustration.

I claim:

The ornamental design for a temperature sensing probe, as shown and described.
